UNITED STATES PATENT OFFICE

2,107,914

ELECTRIC LAMP ATTACHMENT FIXTURE

Albert H. Stricker, Cleveland, and Marshall W. Ulf, Shaker Heights, Ohio, assignors to General Electric Company, a corporation of New York

Application May 29, 1935, Serial No. 24,034

1 Claim. (Cl. 248—4)

Our invention relates to electric lamp fixtures of the type adapted to be attached to tables, desks, machines and other devices. Our fixture is so constructed as to allow ready attachment or detachment thereof and also ready adjustment thereof so as to properly position the light source carried thereby. Such adjustment may be vertical and angular and in the preferred embodiment it may also be horizontal. One of the features of our invention is a tube which is clamped to the table or other device so as to allow vertical adjustment and through which the electrical conductors extend. The said tube is bent to cause the lighting unit carried thereby to be positioned over the work. Various other features and advantages of our invention will appear from the description which follows of a species thereof and from the accompanying drawings.

In the drawings Fig. 1 is a side elevation of the lamp of our invention; Fig. 2 is a side elevation of a portion thereof on an enlarged scale; Fig. 3 is a section along line 3—3 of Fig. 1, also on an enlarged scale; Fig. 4 is a perspective view of a modified supporting means for our lamp; Fig. 5 is a side elevation of a modification of the lamp of our invention; and Fig. 6 is a plan view of a portion thereof with the lamp broken along lines 6—6 of Fig. 5.

The light producing element in our lamp, as shown in Fig. 1, is the incandescent lamp 10 which is mounted in the socket 11 on the end of hollow extension 12. The socket 11 is provided with a husk 13 in which the end of the bowl 14 is fastened by means of thumb screws 15. The bowl 14 is preferably made of translucent opal glass and supports on its upper edge the shade 16 which is preferably opaque and of metal. One end of the extension 12 extends into the end of tube 17 and is clamped in the desired position therein by the shoe 18 which is pushed inwardly by thumb screw 19 as shown in Fig. 2. The screw 19 is threaded in a collar 20 which is carried by the end of tube 17 and which keeps the shoe 18 in line since it straddles the sides of the narrowest portion thereof. The telescoping feature of tube 17 and extension 12 permits the horizontal extent of the lamp to be varied.

The light distributing unit already described is supported in the embodiment shown in Fig. 1 by means of the clamp 21 which is fastened to the top of a table 22, desk or the like, by thumbscrew 23. The tube 17 passes through an aperture in the clamp 21 in which it is secured by thumbscrew 24. The screw 24 permits the light-

ing unit to be raised or lowered or turned to any position desired. The wiring for this assembly comprises the double insulated wire 25 which is connected to socket 11 and passes through tube 17 and extension 12 to the plug 26.

In Fig. 4 is shown a modified supporting means for the light distributing unit. This means comprises clamp 21' which is fastened to the table by thumbscrew 23 and the collar 22' which normally rests against the top of the clamp 21'. The collar 22' fixes the vertical position of the lighting unit and in this instance is attached to tube 17 by means of screw 28 although it may be attached by some more permanent means as no adjustment is usually necessary. A ridge 24' is provided in the lower face of collar 22' which enters into the notch 25' in the clamp 21'. This feature provides means for holding the lighting unit in one position over the table.

The species of our invention shown in Fig. 5 is adapted especially for business machines such as those used in compiling statistics. The light distributing unit in this instance is the same as shown in Fig. 1 and it is supported by a standard comprising collar 27, sleeve 28 and boss 29. The collar 27 and boss 29 are securely fastened to the opposite ends of the sleeve 28 and the end of tube 17 which extends into sleeve 28 is held in position by the thumbscrew 30 which is threaded in an aperture in collar 27 and sleeve 28. The boss 29 is fastened to the strap 31' which with strap 31 forms means for engaging the machine table 32. The ends of the straps are attached to the table 32 by screws 33 and the overlapping ends of the straps are secured to each other by screws 34. The screws 34 are threaded in strap 31 and lie in elongated slots in strap 31' which permits the assembly to be shortened or lengthened to the size of the particular table on which it is used. The electric current for operating the lamp 10 is conducted from some convenient source by the plug 35 and the double insulated wire 36. The wire 36 passes through an aperture in boss 29 and sleeve 28 and through the center of tube 17 and extension 12 to the socket 11.

A rack 37 is provided for holding papers in the most desirable position for the machine operator with reference to both machine and light. The rack 37 is provided with a bracket 38 which engages fitting 39 on the end of rod 40. The rod 40 is supported by a standard comprised of collar 41, sleeve 42 and boss 43, the collar 41 and boss 43 being attached to opposite ends of the sleeve 42 and the boss being attached to strap 31.

31. The rack 37 may be tilted to the angle desired and clamped in place by tightening the wing nut 44 which clamps bracket 38 and fitting 39 together. The height of the rack may be 5 adjusted by moving rod 40 in or out of the standard and then clamping it in place by the thumb-screw 45.

What we claim as new and desire to secure by Letters Patent of the United States is:

- 10 10 A lighting fixture for attachment to tables and like devices comprising a clamp adapted to engage the edge of the top of said table or other device, a hollow bent tube supported in said clamp and comprising a vertically extending portion and a horizontally extending portion, said tube being mounted in said clamp so as to allow

rotation of said tube and movement of said horizontal portion in a horizontal plane, a rigid tubular extension adjustably carried by said horizontal portion, an illumination device comprising a socket rigidly secured to the end of said extension and adapted to hold an incandescent lamp vertically with the base downward, a diffusing shade surrounding said lamp and a reflector surrounding said shade and adapted to direct the light downwardly, said shade and reflector being located above said extension, and electric conductors extending through said tube and extension to said socket.

ALBERT H. STRICKER. 15
MARSHALL W. ULF.
